UNITED STATES PATENT OFFICE.

JULIUS S. MEYER, OF NEW YORK, N. Y., ASSIGNOR TO THE HARTFORD
CARPET COMPANY, OF HARTFORD, CONNECTICUT.

DESIGN FOR A CARPET.

SPECIFICATION forming part of Design No. 14,507, dated December 25, 1883.
Application filed July 28, 1883. Term of patent 3½ years.

To all whom it may concern:

Be it known that I, JULIUS S. MEYER, of New York city, New York, have invented a new and original Design for Carpets, of which 5 the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

15 The ground *a* is loosely filled in with small disconnected radial figures, as shown. On this ground are several large flower-groups.

A consists of a central mass of large open roses and leaves, with ferns and leaf-sprays on either side and a cluster of small flowers and 20 flag-like leaves shooting up above. B is a smaller group, consisting of a mass of open flowers and leaves, with ferns springing out on the left, a cluster of moss-rose buds above, and a trailing leaf-sprig below. Several other 25 flower-groups complete the design.

I claim—
The design for a carpet, substantially as shown and described.

JULIUS S. MEYER.
